Primary Examiner — Karen E Eldridge Powers*Assistant Examiner* — Margaret Leah Bryan(74) *Attorney, Agent, or Firm* — Lewis Brisbois Bisgaard & Smith LLP(57) **CLAIM**

The ornamental design for a electric grinder for nails, as shown and described.

DESCRIPTION

FIG. 1 is a top perspective view of the electric grinder for nails showing the new design;

FIG. 2 is a front elevation view thereof;

FIG. 3 is a back elevation view thereof;

FIG. 4 is a top plan view thereof;

FIG. 5 is a bottom plan view thereof;

FIG. 6 is an enlarged left side elevation view thereof; and, FIG. 7 is an enlarged right side elevation view of the electric grinder for nails.

The broken lines shown are included for the purpose of illustrating the unclaimed portions of the article and form no part of the claim.
